PRICE TAG

Gustaf A. Wallin, Flushing, N. Y., assignor to
 A. Kimball Company, New York, N. Y., a corporation of New York

Application February 27, 1935, Serial No. 8,437

3 Claims. (Cl. 40—25)

This invention relates to price tags and particularly to tags of the type intended to be secured to articles of merchandise in such manner that they cannot be removed therefrom without detection.

It is an object of the invention to provide a price tag of this type which shall provide improved safeguards against removal.

It is a further object of the invention to provide a price tag of this type having a portion adapted to be printed with sales information, which may be attached to the merchandise in either of two positions according to the preference of the user, i. e., protruding outwardly from the edge of the merchandise or lying contiguously to the merchandise.

A preferred embodiment of the invention selected for purposes of illustration is shown in the accompanying drawing, in which,

Figure 1 is a perspective view showing the tag folded and secured as in use.

Figure 2 is a plan view showing the tag partially folded with the staples secured.

Figures 3 and 4 are plan views of the back and front of the tag respectively.

Figure 5 is a section on the line 5—5 of Figure 1 showing one manner of attachment to the merchandise.

Figure 6 is a similar section showing another manner of attachment, and

Figure 7 is a similar section with the end flap unsecured.

Referring to the drawing, the tag comprises a series of flaps 1, 2, 3, and 4 preferably formed from a single piece of relatively heavy paper or cardboard, the flaps being separated by folds 5, 6, and 7. The folds 5 and 7 are folded in the opposite direction from the fold 6 so that the flaps may readily assume a zig-zag relationship in use as illustrated in Figure 1.

The flaps 2, 3, and 4 may be of approximately equal lengths, while the flap 1 which is intended to carry printed matter giving sales information and the like may be somewhat longer so as to provide a substantial area for the reception of printed matter. Preferably the said sales information is printed on the front face of the flap 1 which is illustrated in Figure 4.

Mounted on the flap 1 close to the fold 5 is a wire staple 8 having prongs 9 which are intended to secure the tag to merchandise. The said staple may be of any desired form, the particular staple illustrated in the drawing being one common form used for the purpose.

The flap 2 is provided with a pair of slots 10

of a length sufficient to permit the prongs 9 to pass through without being bent as the tag is attached to the merchandise. The flap 3 is also provided with a pair of apertures 11 adapted to receive the prongs 9, which are thereafter bent over as illustrated in Figure 2 in order to secure the tag to the merchandise.

It will be observed that in view of the arrangement of the flaps previously described, the merchandise may be inserted in the fold between the flaps 1 and 2 as illustrated in Figure 5, or the merchandise may be inserted in the fold between the flaps 2 and 3 as illustrated in Figure 6. If inserted between the folds 1 and 2, the prongs 9 are passed through the merchandise, the flap 2 is then folded down with the prongs passing through the slots 10, and the flap 3 is then folded back with the prongs extending through the apertures 11. The prongs are then bent over as illustrated in Figure 2 and the tag is ready to be sealed as hereinafter described. In this case, as illustrated in Figure 5, the flap 1 extends along the merchandise from the edge thereof, contiguously thereto.

If the merchandise is inserted between the flaps 2 and 3, the flap 2 is first folded down with the prongs extending through slots 10 and the merchandise is then inserted and the prongs are passed through the merchandise. The flap 3 is then folded down with the prongs extending through the apertures 11 and the prongs are bent over as before. In this case, the flap 1 protrudes outwardly from the edge of the merchandise as illustrated in Figure 6.

In order to prevent tampering with the tag, as by opening the prongs of the staple 8, the cover flap 4 is provided which folds over the ends of the prongs so that it is difficult to tamper with them. Preferably the cover flap is secured by a seal which in itself cannot be opened without detection. Various types of seals may be used for this purpose, but the form of seal illustrated herein has been found to be particularly effective for this purpose. This seal, which is particularly described in Laencher Patent No. 1,916,003, dated June 27, 1933, comprises two interlocking members 12 and 13 which are mounted respectively on the flaps 3 and 4. Preferably, the member 12 is located at a distance from the apertures 11 which is less than the length of the prongs, thus preventing the prongs from being bent downwardly. After the tag is pinned to the merchandise as previously described, the seal is closed thus preventing the prongs from being tampered with.

One of the advantages of the tags illustrated herein has to do with the location of the staple 8. In some tags of this general type, the staple is located at a free edge of the tag. It has been found to be possible to remove tags of this type by tampering with the staple at the free edge. In the present form of tag, with the staple close to and covered by the fold 5, it is more difficult to tamper with the staple in this manner.

10 It will be understood that the invention may be variously modified and embodied within the scope of the subjoined claims.

I claim as my invention:

15 1. A price tag comprising a series of connected flaps adapted to be folded in zig-zag relationship, one of the end flaps having a pronged staple mounted thereon close to the next adjacent flap, said next adjacent flap having apertures therein through which the prongs of said staple may pass, the third flap in said series being also provided with apertures through which the prongs of the staple may pass, a cover flap, and means for securing the said third flap and said cover flap together.

20 2. A price tag comprising a series of connected flaps adapted to be folded in zig-zag relationship, one of the end flaps of said series being longer than the other flaps and having a

substantial area for the reception of printed matter, said end flap having a pronged staple mounted thereon close to the next adjacent flap, said next adjacent flap having apertures therein through which the prongs of said staple may pass, the third flap in the series being also provided with apertures through which the prongs of the staple may pass, a cover flap, and means for securing the said third flap and said cover flap together. 10

25 3. A price tag comprising a series of connected flaps adapted to be folded in zig-zag relationship, one of the end flaps of said series being longer than the other flaps and having a substantial area for the reception of printed matter, 15 said end flap having a pronged staple mounted thereon close to the next adjacent flap, said next adjacent flap having apertures therein through which the prongs of said staple may pass, the third flap in the series being also provided with apertures through which the prongs of the staple may pass, a cover flap, the said third flap and the cover flap being provided with interlocking seal members, the seal member in said third flap being located at a distance from 20 the apertures in said flap less than the length of said prongs.

GUSTAF A. WALLIN.
